BELT GUIDE

Robert H. Griffin, Yonkers, N. Y., assignor to
 Tanners Research Corporation, New York,
 N. Y., a corporation of Delaware

Application May 29, 1951, Serial No. 228,910

17 Claims. (Cl. 74—241)

1 This invention relates to guides for maintaining belts or like members in alignment axially of the rolls over which they travel.

The primary object of the invention is to provide an improved guide for belts and the like employing feeler controlled actuated mechanism for automatically resisting creepage.

Another object of the invention is to provide an improved guide for belts and the like wherein a cam actuated control, responsive to an edge-feeler, automatically actuates mechanism by which a supporting roll is swung to overcome creepage.

An additional object of the invention is to provide a guide for belts and the like having a lost motion connection between an edge feeler and a control valve whereby a fluid pressure cylinder actuated guide roll is enabled to reduce creepage to a minimum.

A further object of the invention is to provide a guide for belts having a pin and slot connection for camming a guide roll controlling valve to operative position whereby a minimum creepage of a belt produces a maximum restoring force in the guide roll.

Another object of the invention is to provide a guide for belts and the like utilizing fluid pressure for automatically actuating a guide roll, wherein the extent and sensitivity of the alignment restoring force is readily adjustable to control the extent of creepage.

Other objects and advantages of the invention will appear hereinafter in the detailed description, be particularly pointed out in the appended claims, and illustrated in the accompanying drawings in which:

Figure 1 is a front elevational view of a preferred form of the belt guide of the present invention;

Figure 2 is a vertical sectional view taken along the lines 2—2 of Figure 1;

Figure 3 is a fragmentary horizontal sectional view taken along the lines 3—3 of Figure 1;

Figure 4 is a fragmentary vertical sectional view on an enlarged scale, taken along the lines 4—4 of Figure 1, with parts shown in elevation to more clearly illustrate certain of the details of construction;

Figure 5 is a vertical sectional view taken along the lines 5—5 of Figure 4;

Figure 6 is a plan view of the control mechanism of Figure 4;

Figure 7 is a horizontal sectional view taken along the lines 7—7 of Figure 5; and

Figure 8 is a schematic view showing the rela-

2 tion between the control valve and the actuating cylinder.

Referring now in detail to the drawings in which like reference characters designate like parts, the improved guide of the present invention is adapted to guide belts, strips and other members, which in traveling over one or more supporting rolls tend to creep or track out of alignment axially of the rolls, such members hereinafter being collectively termed belts. In the illustrated form of the invention, the improved guide is comprised of a guide roll 1 over which a belt 2 travels. Depending upon its application, the guide roll 1 may be either a drive or an idler roll, the latter being preferred for simplicity of construction and the roll preferably being positioned to engage and support the belt intermediate fixed driving and driven rolls in the manner illustrated in my copending application Serial No. 159,436, filed May 2, 1950.

The guide roll 1 is suitably journaled in a yoke 3 surmounting or supported by a support member 4 and connected thereto by a center bearing 5, the center pin 6 of the bearing being positioned to enable the guide roll to swivel or pivot horizontally about a central vertical axis. The support member, in turn, may be supported on or between the sides 7 of a suitable frame to which its ends are attached by mounting brackets 8. For swiveling or pivoting the guide roll about its axis, there is provided an air or other fluid pressure actuating cylinder 9 which may conveniently be swivelly anchored to an outrigger 10 fixed to the support member 4 and has the free end of its piston rod 11 swivelly connected to the base 12 of the yoke 3 adjacent one of its ends.

The control mechanism by which the actuating cylinder 9 is actuated to swivel the guide roll 1 is comprised of a pair of feelers 13, disposed on either side of or straddling the belt 2 and each engaging or contacting an edge of the belt as it creeps to that side. To minimize friction between the belt and the feelers, the latter are preferably rollers rotatable about axes normal to the travel of the belt and each mounted on a supporting block 14. Both blocks are slidably mounted on a common guide shaft or rod 15, one end of which is slidably or reciprocally received in a sleeve bearing 16 attached to one of the sides 7 of the frame. The shaft 15 extends below and substantially normal or perpendicular to the path of travel of the belt 2 and is spaced from the guide roll 1 sufficiently to prevent interference with swivelling of the latter. The positions 55 of the feeler rollers 13 axially of the shaft 15

and therethrough their spacing laterally relative to the edges of the belt are made settable by set screws 17 carried by their supporting blocks 14.

The end of the shaft 15 opposite that received in the sleeve bearing 16 is releasably fixed in an upper web 18 of a cap member 19 by a taper pin 20, the cap member below its web, being bifurcated and having its spaced legs 21 welded or otherwise fixed to the upper face of a cam or sliding plate 22 adjacent the opposite sides thereof. As shown, the cam plate 22 is slidable or reciprocable between spaced side elements 23 of a guide plate 24, the cam and guide plates being interlocked against other than such movement by beveling the edges 25 of the cam plate and correspondingly forming the confronting walls 26 of the guide plate. Sliding friction between the engaging surfaces of the cam and guide plates is preferably reduced by the provision of a pair of oilers 27 each mounted on one of the side elements 23 of the guide plate 24 and connected to a passage 28 leading through the associated element to the adjacent engaging surfaces of the plates. For fixing its position, the guide plate 24 is bolted to a base 29 attached to the adjacent of the sides 7 of the frame.

Also mounted on and shiftable or slidable relative to the base 29, normal to the path of movement of the cam plate 22, is a carriage 30. This carriage is formed of a pair of horizontally spaced end plates 31 joined by vertically spaced connecting rods 32, each of which is guided in a pair of horizontally spaced projections or lugs 33 outstanding from the base 29, the connecting rods being supported in the lugs in bushing 34 of the self-lubricating type, which are held in place by retainers 35.

For transferring movement of the cam plate 22 to the carriage 30, the cam plate is slotted longitudinally to provide a cam slot 36, straddled by the legs 21 of the cap member 19 and having elongated relatively offset end portions 37 connected by a diagonally or angularly disposed or inclined central portion 38. Within this slot is adapted to slide or ride a cam pin or bolt 39 which is secured to and upstanding from the upper edge of the underlying one of the end plates 31 of the carriage 30. To facilitate relative movement of the cam and end plates 22 and 31, a roller or sleeve bearing 40 is interposed between the cam pin 39 and the edges of the cam slot 36 and flat bearings 41 are inserted between the confronting faces of cam and end plates and between the upper end of the sleeve 40 and a cotter pin 42 by which it is held in place.

With the cam plate 22 and the carriage 30 so connected, and the cam pin 39 normally riding midway of the inclined central portion 38 of the cam slot 36, movement of the cam plate on the application of force to the guide shaft 15 through one of the feeler rollers 13 will immediately shift the carriage 30 transversely of the cam plate. This shifting continues until the cam pin 39 reaches one of the elongated end portions 37 of the cam slot, whereafter the carriage will be held in its shifted position regardless of further outward movement of the cam pin, remaining in that position until the cam pin is returned to the central portion 38 of the slot by corresponding movement of the guide shaft 15 by the feeler rollers 13.

Shifting of the carriage 30 in response to reciprocal movement of the guide shaft 15 is in turn employed to operate a control valve 43 by

which swivelling of the guide roll 1 by the actuating cylinder 9 is controlled. The control valve is mounted on the base 29 within the carriage 30 and for sensitivity preferably has the lands 44 of its piston 45 so arranged relative to the several inlets and outlets that the components of the fluid pressure, axially of the piston, are in balance throughout movement of the piston in the valve body 46. Additionally, due to the lost motion between the cam plate 22 and the carriage 30 permitted by the elongation of the end portions 37 of the cam slot 36, it is possible to hold the spacing between the lands 44 to a minimum, enabling the relatively slight movement of the cam pin within the central portion 38 of the cam slot to apply the force by which the piston is moved to either terminal position.

In the form shown, the control valve 43 has an entrance port 47 and a bleed or exhaust port 48, which are selectively connectable by a pair of conduits 49 to opposite ends of the actuating cylinder 9 through corresponding outlet ports 50 in the valve body 46, these conduits serving either to charge or to bleed their respective ends of the actuating cylinder, depending upon the position of the piston 45. Not only does the illustrated valve lend itself to quick-opening, but the extent of the opening of each of its outlet ports 50 and thereby the pressure applied at the ends of the actuating cylinder, are individually adjustable by stop nuts 51, one threadedly engaging each end of the piston 45, exteriorly of the valve body 46.

While the aforementioned lost motion connection between the cam plate 22 and the carriage 30 permits the piston 45 to be connected directly to the carriage, it has been found preferable to employ a yieldable connection by spring loading the valve so that the force of the carriage is cushioned as it is transmitted to the control valve 43. This is accomplished by attaching to either end of the piston 45 a stem or extension 52, each of sufficient length to extend through an aperture 53 in the adjacent of the end plates 31 and be slidably received therein by a self-lubricating bushing 54 held by a retainer 55. Both stems are threaded over their inner end portions to receive adjusting nuts 56 and are encircled between these nuts and the confronting walls of the corresponding end plates 31 by coil springs 57, adjustment of the nuts, by controlling the precompression of the springs, determining their resiliency and thus the extent to which they cushion the impact of the carriage 30 on the control valve. Since, as one end plate of the carriage moves toward the control valve, the other end plate moves away, the spring under load is enabled to transmit the force applied to it without resistance from the opposite spring, the latter being relieved of pressure as the former is loaded.

The inter-action of the control valve 43 and the actuating cylinder 9 can best be understood by reference to the schematic view of Figure 8. As there shown, pressure is applied through the entrance port 47 of the control valve and, in the illustrated position of the piston 45, is directed through the right-hand of the outlet ports 50 into the closed end of the actuating cylinder 9, moving the actuating piston 58 towards the opposite ends of the cylinder. During this movement, back pressure is eliminated by venting the fluid behind the actuating piston 58 through the other of the conduits 49 to the bleed port 48. In the illustration, the stop nut 51 abutting the

end of the valve body 46 has been adjusted to permit full opening of the associated outlet port 50. By merely turning the stop nut inwardly, the travel of the piston in that direction can be limited as desired to restrict the outlet port, if slower action of the actuating cylinder 9 is wanted without adjustment of the pressure in the fluid line. A corresponding adjustment can, of course, be made for the reverse action of the actuating piston 58 by turning in the other of the stop nuts 51. To enable the desired adjustment of the stop nuts 51 and the adjusting nuts 56 to be maintained, both are provided with set screws 59 by which they are lockable, respectively, to the piston 45 and stems 52.

In operation, the feeler rollers 13 are set on the guide shaft 15 either in contact with or spaced from the edges of the belt 2, depending on the extent of tracking to be permitted before restoring force is applied to the belt. With the rollers so set, creepage of the belt toward either side out of its normal travel, will apply lateral pressure against one of the feeler rollers and, therethrough, cause the guide shaft 15 to shift correspondingly transversely of the belt. As the shaft 15 starts to move, carrying with it the cam plate 22, the cam pin 39 is dislodged from its position centrally of the cam slot 36 and moves towards one of the elongated end portions 37. In so moving the cam pin causes the carriage 38 to shift relative to the control valve 43, loading one of the springs 57 and shifting the piston 45 correspondingly.

Assuming the movement of the belt to have been in the direction indicated by the position of the control piston 45 in Figure 8, for which the belt 2 would have tracked toward the left side of the guide roll of Figure 1, the actuating cylinder 9 immediately begins to swivel the guide roll clockwise about the center pin 6, enabling the guide roll to drive the belt back to normal alignment. Since the lost motion between the cam pin 39 and the cam slot 36 occurs after pressure has been applied to the actuating cylinder and not before through excessive spacing of the lands of the piston of the control valve, as would be necessary were the guide shaft connected directly to the piston of the valve, a maximum restoring force is obtained almost immediately on the start of creepage. The belt guide of the present invention is thus enabled to hold creepage at a minimum, as well as to prevent over-driving of the belt by the guide roll, adapting it especially for guiding belts over short unsupported spans where the delayed action of the usual belt guide is a definite handicap.

From the above detailed description it will be apparent that there has been provided an improved guide for belts and the like which is extremely sensitive to creepage and, while enabled to apply maximum restoring force to a belt on slight creepage, is adapted to absorb the limits of the creepage without causing binding of the belt. It should be understood that the described and disclosed embodiment is merely exemplary of the invention and that all modifications are intended to be included which do not depart either from the spirit of the invention or the scope of the appended claims.

Having described my invention, I claim:

1. A belt guide comprising a swivelable guide roll for engaging and guiding a belt, feeler means displaceable by said belt on creeping thereof, a control valve, means connecting said feeler means and control valve for operating said

valve on displacement of said feeler means by said belt, and actuating means controlled by said control valve for swiveling said guide roll to counter the direction of creepage of said belt, said connecting means including lost motion means for absorbing further creepage of said belt without affecting operation of said control valve.

2. A belt guide comprising a swivelable guide roll for engaging and guiding a belt, feeler means engageable with said belt and displaceable thereby on creeping thereof, a control valve, a lost motion connection between said feeler means and control valve for actuating said valve on displacement of said feeler means while absorbing further displacement thereof without interference with said valve, and fluid pressure means controlled by said control valve for swiveling said guide roll in a direction to drive said belt back to normal position.

3. A belt guide comprising a guide roll engageable with a belt, means for swinging said guide roll about an axis normal to said belt, feeler means engageable with said belt and displaceable thereby on creeping thereof, a control valve, and a lost motion connection between said feeler means and control valve for actuating said valve on displacement of said feeler means and absorbing further displacement of said feeler means without affecting actuation of said control valve, said control valve controlling swinging of said guide roll by said swinging means for driving said belt back to normal position.

4. A belt guide comprising a swivelable guide roll for engaging and guiding a belt, feeler means engageable with said belt and displaceable thereby on creeping thereof, a control valve, a pin and slot cam connection between said control valve and feeler means for actuating said valve in response to displacement of said feeler means, and fluid pressure means controlled by said control valve for swiveling said guide roll to restore said belt to normal position.

5. A belt guide comprising a swivelable guide roll for engaging and guiding a belt, feeler means engageable with said belt and displaceable thereby on creeping thereof, a member displaceable with said feeler means and having a cam slot, a cam pin ridable in said cam slot, a control valve connected to said cam pin and operable therethrough in response to displacement of said feeler means, and fluid pressure means controlled by said valve for swiveling said guide roll in a direction to restore said belt to normal position.

6. A belt guide comprising a swivelable guide roll for engaging and guiding a belt, feeler means engageable with said belt and displaceable thereby on creeping thereof, a member displaceable with feeler means and having a cam slot, a cam pin ridable in said cam slot, a control valve yieldably connected to said cam pin and operable therethrough in response to displacement of said feeler means, and fluid pressure means controlled by said valve for swiveling said guide roll in a direction to restore said belt to normal position.

7. A belt guide comprising a swivelable guide roll for engaging and guiding a belt, feeler means engageable with said belt and displaceable thereby on creeping thereof, a member displaceable with feeler means and having a cam slot, a cam pin ridable in said cam slot, a control valve, cushioning means interposed between and connecting said control valve and cam pin for operating said valve in response to displacement of said feeler means, and fluid pressure means control-

led by said valve for swiveling said guide roll in a direction to restore said belt to normal position.

8. A belt guide comprising a swivable guide roll for engaging and guiding a belt, a guide shaft spaced from said guide roll and reciprocable transversely of said belt, a pair of spaced feelers mounted on said shaft and disposed to engage opposite edges of said belt, a control valve, a lost motion connection between said control valve and shaft for operating said valve in response to displacement of said feelers by creeping of said belt, and actuating means controlled by said control valve for swiveling said guide roll to restore said belt to normal position.

9. A belt guide comprising a swivable guide roll for engaging and guiding a belt, a guide shaft spaced from said guide roll and reciprocable transversely of said belt, a pair of spaced feeler rollers mounted on said shaft and disposed to engage opposite edges of said belt, a control valve, a lost motion connection between said control valve and shaft for operating said valve in response to displacement of said feeler rollers by creeping of said belt, and actuating means controlled by said control valve for swiveling said guide roll to restore said belt to normal position.

10. A belt guide comprising a swivable guide roll for engaging and guiding a belt, a guide shaft spaced from said guide roll and reciprocable transversely of said belt, a pair of feeler rollers carried by said guide shaft and disposed to engage opposite edges of said belt, a control valve, cam means connecting said valve and shaft for operating said valve in response to displacement of said feeler rollers by creeping of said belt, lost motion means associated with said cam means for absorbing additional creepage of said belt, and actuating means controlled by said valve for swiveling said guide roll to restore said belt to normal position.

11. A belt guide comprising a swivable guide roll for engaging and guiding a belt, a pair of feeler rollers associated with said roll and disposed to be engaged and displaced by opposite edges of said belt on creeping thereof, a control valve, a lost motion connection between said control valve and feeler rollers for operating said valve in response to displacement of said feeler rollers by creeping of said belt, and actuating means controlled by said control valve for swiveling said guide roll and restoring said belt to normal position.

12. A belt guide comprising a swivable guide roll for engaging and guiding a belt, a pair of feeler rollers associated with said guide roll and disposed to be engaged and displaced by opposite edges of said belt, a cam member displaceable with either of said feeler rollers and having a cam slot elongated at either end, a cam pin ridable in said slot, a carriage mounting said pin and shiftable therewith transversely of said slot on displacement of said cam member, a control valve operatively connected to said carriage and operated on shifting thereof, and an actuating cylinder controlled by said control valve for swiveling said guide roll to restore said belt to normal position.

13. A belt guide comprising a swivable guide roll for engaging and guiding a belt, a pair of feeler rollers associated with said guide roll and disposed to be engaged and displaced by opposite edges of said belt, a cam member displaceable with either of said feeler rollers and having a

cam slot elongated at either end, a cam pin ridable in said slot, a carriage mounting said pin and shiftable therewith transversely of said slot on displacement of said cam member, a control valve, yieldable means operatively connecting said control valve to said carriage for operating said carriage in response to displacement of said feeler rollers, and an actuating cylinder controlled by said control valve for swiveling said guide roll to restore said belt to normal position.

14. A belt guide comprising a swivable guide roll for engaging and guiding a belt, a pair of feeler rollers associated with said guide roll and disposed to be engaged and displaced by opposite edges of said belt, a cam member displaceable with either of said feeler rollers and having a cam slot elongated at either end, a cam pin ridable in said slot, a carriage mounting said pin and shiftable therewith transversely of said slot on displacement of said cam member, a control valve, adjustable yieldable means operatively connecting said control valve to said carriage for operating said carriage in response to displacement of said feeler rollers, and an actuating cylinder controlled by said control valve for swiveling said guide roll to restore said belt to normal position.

15. A belt guide comprising a shiftable guide roll for engaging and guiding a belt, feeler means engageable with said belt and displaceable thereby on creeping thereof, a shiftable carriage, a pin and slot connection between said feeler means and carriage, control means operatively connected to said carriage and operated by shifting thereof in response to displacement of said feeler means, and actuating means controlled by said control means for shifting said guide roll to restore said belt to normal position.

16. A belt guide comprising a shiftable guide roll for engaging and guiding a belt, a guide shaft spaced from said guide roll and reciprocable transversely of said belt, a pair of spaced feelers carried by said guide shaft and straddling said belt, said feelers and therethrough said guide shaft being displaceable by said belt on creeping thereof, a shiftable carriage, a pin and slot connection between said carriage and shaft for shifting said carriage in response to displacement of said feelers, control means operated by shifting of said carriage, and actuating means controlled by said control means for shifting said guide roll to restore said belt to normal position.

17. A belt guide comprising a shiftable guide roll for engaging and guiding a belt, a guide shaft spaced from said guide roll and reciprocable transversely of said belt, a pair of spaced feelers carried by said guide shaft and straddling said belt, said feelers and shaft being displaceable by said belt on creeping thereof, a shiftable carriage, cam means connecting said carriage and shaft for shifting said carriage, control means operated by shifting of said carriage, and actuating means controlled by said control means for shifting said guide roll to restore said belt to normal position.
